E. A. SPAULDING

PERFORATING MACHINE

Filed March 30, 1923

Inventor: Eugene A. Spaulding
by S. M. Bates, Mfg.

UNITED STATES PATENT OFFICE.

EUGENE A. SPAULDING, OF PORTLAND, MAINE.

PERFORATING MACHINE.

Application filed March 30, 1923. Serial No. 628,735.

To all whom it may concern:

Be it known that I, EUGENE A. SPAULDING, a citizen of the United States, residing at Portland, in the county of Cumberland and State of Maine, have invented certain new and useful Improvements in Perforating Machines, of which the following is a specification.

My invention relates to feeding attachments for perforating machines such as are used for perforating paper for bank checks, postage stamps and the like.

These machines are provided with a multiple perforating die and a feed table upon which the paper rests.

The perforations are made parallel lines and at varying intervals from each other and means are provided for feeding the paper a few sheets at a time along the surface of the table to the perforating die.

The feeding is done by means of a so-called apron which is a flat strip of metal extending across the table from side to side and parallel with the perforating die. The apron is supported closely adjacent to the surface of the table by a shaft to which it is journalled and which also extends across the table with a pinion at each end engaging a pair of racks, one at each side of the table and both at right angles to the die. In this way, both ends of the apron are moved toward the perforating die at exactly the same rate of speed and the apron is always parallel with the die.

To quickly locate the apron at the desired spot, a pawl is provided with a series of stops which may be located at varying distances from the perforating die, each stop having a fixed surface or a shoulder against which the pawl may be pressed to accurately locate the position of the apron.

The pawls or stops are so constructed that the pawl and its connecting apron may be pushed toward the perforating die, the pawl passing freely over the stop but the motion of the apron back and away from the die will be checked by the stop. In actual operation, the apron is pushed at each operation toward the die slightly beyond the stop and then brought back against the stop to bring it to the operative position.

Means are provided for releasing the pawl so that the apron may slide freely backward.

It will be understood that in feeding the paper through the perforator the operator

stands in rear of the table and places both hands with their fingers resting on the paper which in turn rests on the apron.

During the feeding of the paper, it is important that the paper be held absolutely rigid on the apron and that it should not be disturbed from its original position.

My improvement is directed more particularly to the releasing mechanism whereby the pawl is released from the stop by the action of either of the hands of the operator and without removing either hand from its position while holding the paper on the apron where it should be steadily held during the feeding operation.

This is accomplished by means of a spacing bar extending along parallel to the apron in position where it can be easily operated by either hand or arm of the operator, the spacing bar having connections for releasing the pawl each time it is touched by the operator.

In the old machines, it has always been necessary for the operator when he released the pawl for the purpose of moving the apron backward to remove at least one of his hands from contact with the paper so that the latter was liable to be disturbed or displaced while the operator's hand was not in contact with it.

Another object of my invention aside from the one already mentioned is to provide a stop and a rail for containing the same with means for quickly changing the location of the stops for locating the line of the perforations.

Another purpose of the invention is to provide the feed racks with teeth underneath instead of being on top of the same and pinions on the feed shaft engaging said racks with means for adjusting the pinions and the ends of the shaft vertically to insure the perfect running of the shaft and pinions with relation to the rack and with means for taking up wear that might take place between the pinions and the rack.

These several features of my improvement will be more specifically pointed out hereinafter and the novel features thereof claimed in the appending claims.

In the accompanying drawing, I have illustrated a feeding mechanism constructed in accordance with my invention in which:

Fig. 1 is a plan,

Fig. 2 is a rear elevation,

Fig. 3 is an end elevation,

Fig. 4 is a section on the line 4—4,
Fig. 5 is a section on the line 5—5 of
Fig. 1,

Fig. 6 is a plan of the stop and,
5 Fig. 7 is a section on the line 7—7 of
Fig. 6.

Referring to the drawing, 1 represents the feed table upon which a feeding apparatus is secured. Secured on top of the table and 10 extending back from the perforator are the two feed rails 2 and 3 spaced apart far enough to permit the feeding mechanism to be placed or supported between them. Each of the rails 2 and 3 carries a rack 4 having 15 its teeth on the under side and engaging the teeth of each rack is a pinion 5 secured on the opposite ends of a feed shaft 6.

This feed shaft extends substantially the 20 whole width of the table and insures the constant parallelism of the feed mechanism. Each end of the shaft is journaled in a carriage which runs on a slide rail formed as a part of the feed rails 2 and 3. The carriage 7 runs on a slide rail 8 of the feed 25 rail 3 and the carriage 9 runs on the slide rail 10 of the feed rail 2. Means are provided by which the pinion 5 may be raised or lowered slightly with respect to the carriage 9 or 7.

30 For this purpose, a series of screws 11 extend down through the carriages 9 and 7 bearing on a gib 12 on the top of the rails 8 and 10.

By adjusting the screws 11, the pinions 35 are slightly lifted or lowered so that any wear taking place may be compensated for.

The two carriages are united by the shaft 13 fixed in sockets 14 and 14' one on each 40 of the carriages and by the shaft 6. The two carriages are thus united into a solid structure adapted to slide on the rails 8 and 10 toward and away from the perforating punch.

The few sheets of paper operated on rest 45 at their rear end on the apron 16 which is a thin metal bar extending across the machine and uniting the carriages 7 and 9.

At the rear edge of the apron 16 is secured 50 a longitudinal bar 17 extending the entire length of the apron and supporting a lateral guide 18 which is adapted to slide along its upper edge being clamped in place by a clamping screw 19.

This guide has at its forward end a guide 55 finger 20 for guiding the lateral edges of the sheets of paper.

The rear edges of the sheets of paper 21 operated upon rest on the apron 16 and are held in contact with a guide bar 22 which 60 extends across the apron. The fingers of the operator when the machine is in operation rest upon the paper and hold it in contact with the apron 16, keeping its rear edge pressed steadily against the guide 65 bar 22.

The dotted lines 4, 4 and 5, 5 in Fig. 1 show the lateral outlines of the sheets of paper as the side edges rest in contact with the lateral guide 20. The paper is stopped at any desired point as it is fed toward the 70 perforator by stops 23 sliding in inverted T-shaped grooves 24 formed in the feed rail 2. Extending down through each of the stops 23 is a screw 25, the lower end of the screw being adapted to contact with the 75 bottom of the groove.

As the screw is screwed downward, the stop is lifted against the interior surface of the inverted T-shaped groove and is thereby held in place.

A spring pawl 26 is pivoted to the carriage 9 with its operative end sliding along the top of the rail 2 so that it will come in contact with the stops 23 at suitable points.

The relative position of the pawls and the stops is such that as the paper is moved toward the perforator, the pawls slip over the upper ends of the stops and act to check the motion of the apron and to hold the paper accurately in place as it is pulled 90 back. Thus, in feeding the paper, it is fed a short distance beyond each stop as it slides under the perforator and then is drawn back to its real position against the stop.

A spring 27 on the inside of the carriage (see Fig. 4) acts to draw the pawl downward, the spring being secured by one end to the carriage and by the other end to the angle bar 28 which is secured to the end of the shaft 29 which stop extends through the carriage 9 to the pawl on the opposite side of the carriage.

The end of the angle bar 28 rests on the end of a lever 30 which is secured to the shaft 13, this rod being journaled in the two opposite carriages so that it may be rotated slightly.

The rotation of the shaft 13 will tend to lift the end of the lever 30 and raising the end of the bar 28 will lift the free end of the pawl.

The shaft 13 is rotated slightly by means of a spacing bar 31 connected at each end with an operating lever 32 secured to the 11 bar 13.

The result of this arrangement is if the bar 31 is touched or actuated at any point, motion is communicated to lift the pawl and allow the carriage to pass over the stops.

I claim:—

1. In a perforating machine, the combination of a feed table, a feed bar, a feed shaft journaled to said bar, pinions on the ends of said shaft, parallel racks on said table engaged by said pinions, a pawl carried by said bar, a guide extending along the table in the direction of the feed, said pawl being adapted to be carried along adjacent to said guide, a stop adjustably secured on said 13

guide to engage said pawl and a spacing bar extending longitudinally of said feed bar connected to disengage said pawl from said stop.

- 5 2. In a perforating machine, the combination of a feed table, a feed bar, a feed shaft journalled to said bar, pinions on the ends of said shaft, parallel racks on said table engaged by said pinions, a guide rail ex-

tending along the table in the direction of 10 the feed, a pawl carried by said bar and sliding on said rail, a stop adjustably secured to said rail for engaging said pawl, a spacing bar extending parallel with said feeding bar connected to lift said pawl free 15 from said stop.

EUGENE A. SPAULDING.
